UNITED STATES PATENT OFFICE.

OSCAR O'NEAL, OF FREMONT, MICHIGAN.

RAIL-JOINT.

No. 895,294.

Specification of Letters Patent.

Patented Aug. 4, 1908.

Application filed July 23, 1907. Serial No. 385,165.

To all whom it may concern:

Be it known that I, OSCAR O'NEAL, a citizen of the United States, residing at Fremont, in the county of Newaygo and State of Michigan, have invented new and useful Improvements in Rail-Joints, of which the following is a specification.

This invention relates to joints for railroad rails; and it has for its objects to provide a joint of simple and improved construction whereby the ends of abutting rails will be supported firmly against displacement.

With these and other ends in view which will readily appear as the nature of the invention is better understood, the same consists in the improved construction and novel arrangement and combination of parts which will be hereinafter fully described and particularly pointed out in the claims.

20 In the accompanying drawing has been illustrated a simple and preferred form of the invention; it being, however, understood that no limitation is necessarily made to the precise structural details therein exhibited, 25 but that changes, alterations and modifications within the scope of the claims may be resorted to, when desired.

In the drawings:—Figure 1 is a top plan view showing the application of the invention to the abutting ends of two rails. Fig. 2 is a bottom plan view of the same. Fig. 3 is a transverse sectional view taken on the plane indicated by the line 3—3 in Fig. 1.

Corresponding parts in the several figures 35 are denoted by like characters of reference.

The improved rail joint is composed of two principal members namely the chair A and a shoe or binding member B. The chair A comprises a vertically disposed rail-web engaging plate or member 1 having a laterally extending flange 2 adapted to rest upon the foot flange of the rail, adjacent to the inner side of the latter. The chair A is provided with supporting plates 3—3 and 4, extending laterally from the marginal edge of the flange 2 beneath the rail, which latter is designated C; the plates 3—3 being disposed at the ends of the chair, and the plate 4 midway between the ends. The chair is formed with transversely disposed webs or flanges 5—5 at the ends thereof, adjacent to the supporting plates 3—3, and with intermediate webs or flanges 6—6 adjacent to the ends of the sup-

formed to surround the chair except upon the 55 side of the latter abutting upon the rail. These flanges are integral with the chair, which preferably consists of a heavy casting, and said flanges will greatly strengthen and reinforce the said chair, and enable it to resist any stress or strain to which the rail supported thereby may be subjected.

The shoe or binding member B, which is adapted to be supported upon the ends of the plates 3—3 and 4 that project beyond the 65 rail flange, is provided with a web-engaging flange 7 at its inner edge and with a strengthening flange 8 near its outer edge; said flanges being connected with each other by end flanges 9. The flanges 1 and 7 of the 70 chair A and the shoe B respectively are adapted to engage the under side of the head 10 of the rail, which is thereby supported. The parts, when assembled, are connected by bolts 11 extending through the flanges 1 75 and 7 and through the web of the rail; other bolts, 12, being used to secure the shoe B upon the supporting plates 3 and 4 of the chair.

The end flanges 9 of the shoe are formed in 80 alinement with the webs or flanges 5 at the ends of the chair; and the shoe is provided with a centrally thickened or reinforced portion 13 at its central portion, extending between the webs 6—6 of the chair, this 85 being the point which is subjected to the greatest strength. The vertically disposed webs 5 and 6 adjacent to the supporting plates 3 and 4 will greatly reinforce said supporting plates, and render breakage practically impossible under the stress to which the joint will be subjected in practice.

90 The operation and advantages of this invention will be readily understood from the foregoing description taken in connection 95 with the drawings hereto annexed, by those skilled in the art to which it appertains. The construction of the improved joint is simple and effective, and it is easily applied in position for operation.

100 Having thus described the invention, what I claim as new, is:—

In a rail joint a chair comprising a web-engaging plate, a foot flange, rail supporting plates extending from the marginal edges of 105 the latter, and transversely disposed vertical webs on the supporting plates; a shoe or

flange, a strengthening flange spaced therefrom, connecting flanges at the ends thereof and an intermediate thickened or reinforced portion; and connecting members extending through the web-engaging portions of the shoe and the chair, and through the shoe and the rail supporting plates of the chair.

In testimony whereof, I affix my signature in presence of two witnesses.

OSCAR O'NEAL.
